UNITED STATES PATENT OFFICE.

SMITH A. STOUFFER, OF KINGVIEW, PENNSYLVANIA.

ROAD MACHINE.

Application filed August 31, 1926. Serial No. 132,819.

This invention relates to an improved machine for use in constructing a concrete roadway.

In constructing work of this kind, tracks are provided, the rails of which are located on the longitudinal edge portion of the concrete filled, these serving to accommodate the various kinds of machinery which usually embody supporting rollers to permit proper shaping of the surface of the road.

The difficulty with the usual machinery is that the supporting wheels are affixed by respect to each other and inasmuch as the distance between the rails varies, particularly on curves and bends in the road, the machine would run off of the tracks.

What I propose to do is to provide a novel supporting structure including self adjustable axles carrying the track wheels, together with the novel gearing for rotating the axle and simultaneously permitting sliding in order to accommodate the variation in distance between the rails of the track.

The particular details and their relative arrangement will become apparent from the following description and drawings.

In the drawings:—

Figure 1 is a top plan view of a machine constructed in accordance with the invention,

Fig. 2 is a front elevation,

Fig. 3 is an end elevation of the same, on an enlarged scale,

Fig. 4 is a detail view showing the axle construction and driving means,

Fig. 5 is a detail view showing retaining means for the axle,

Fig. 6 is a perspective view of one of the axle sections,

Fig. 7 is an enlarged cross section, taken approximately on the line 7—7 of Fig. 5.

Referring to the drawings in detail, it will be seen that the supporting frame embodies a pair of spaced parallel tubes 1 connected together by cross ties 2, which are simply in the form of narrow strips of metal provided with U-shaped clamping bolts 3. The tie strips extend beyond the tubes and serve to support driven shafts 4 having driving gears or pinions 5 on their outer ends. Supported on the central cross strips 2 is a platform 6 for a motor or other source of power 7 which through the medium of the means 8 including sprockets and sprocket chains, serves to drive the shafts 4.

There are four axle sections 9 provided in the present arrangement, and each section telescopes slidably into one end portion of one of the tubes 1. The tubes 1 thus function as axle housings. It will be noticed from Fig. 6, that each axle includes a groove 10 at its inner end, a key seat 11 at its opposite end, and longitudinal driving ribs 12 between its ends. Secured by a key 65 to the outer end of each axle is a grooved traction wheel 13 adapted to ride upon the rails 14. Then as shown in Fig. 5, the inner portions of the opposed axle sections are arranged in the axle housing and in one 70 instance, one axle section is made fast against longitudinal movement by placing a small retaining pin 15 through one of the openings 16 in the axle housing and permitting the inner end of the pin to project into 75 the groove 10. This prevents that particular section from longitudinal sliding, and yet permits rotation.

The other axle section is not anchored in this way, but is permitted to simultaneously 80 slide and rotate. The disks 12 are so located as to mesh with the teeth of the complimentary gears or pinions 5. Consequently, power will be imparted from the source 7 through the shaft 4, and gear 5 to the axle 85 section by means of the driving ribs 12. At the same time, this axle will be allowed, while being driven, to slide in and out of the axle housing to render it self-adjustable 90 to the varying distances existing between 90 the rails of the tracks.

From the foregoing description and drawings, it will be seen that I have evolved and produced a structure for use in road construction work, wherein the wheels supporting axles are automatically adjustable and wherein the flanges of the wheels form a longitudinal groove in the outer top surface of the roadway as shown in Fig. 2, in order to remove the sharp corner that is 100 otherwise present.

It is believed that by considering the device as described and shown, persons familiar with structures of this kind will be able to obtain a clear understanding of the features, 105 advantages, and operation. Consequently, a more lengthy description is thought unnecessary.

Having thus described my invention, what I claim as new is:—

1. In a supporting structure of the class described, a hollow axle housing, a driving

- shaft located in spaced parallelism in the housing, means for driving said shaft, gears on the outer ends of the shaft, and located beyond the outer ends of the axle housing,
5 a pair of shaft sections telescopically and rotatably mounted in the axle housing, the outer end portion of the shafts being provided with longitudinal driving ribs in mesh with the teeth of said gears, and driving
10 wheels on the outer ends of said axle.
2. In a structure of the class described, a pair of spaced parallel hollow axle housings, cross strips connecting said housings together, said cross strips being longitudinally spaced from each other and extend beyond the axle housing, a pair of shafts mounted for rotation in the extending portions of the cross strips, gears on the outer ends of the shafts located beyond the outer
15 ends of the axle housings, a platform carried by the central cross strips, a source of power mounted on said platform, driving connec-
20

tions between the source of power and the central portions of the shafts, a plurality of axle sections, there being two sections 25 mounted in each axle housing, means whereby either shaft section may be held against longitudinal sliding movement, the outer end portions of the axle sections being provided with longitudinal driving ribs in driving connection with the teeth of said gears, and grooved traction wheels carried by the outer ends of said axle sections.

3. In a road machine of the class described, a supporting structure including an 35 axle housing, an axle slidable and rotatable in said housing and formed with longitudinal driving ribs, a driving wheel fixed to the outer end of the axle, a gear meshing with the ribs of the axle, and means for driving 40 said gear.

In testimony whereof I affix my signature.

SMITH A. STOUFFER.
